UNITED STATES PATENT OFFICE.

WILLIAM HENRY BARRON, JR., OF ATLANTIC CITY, AND CARL LESEMAN, OF EGG HARBOR CITY, NEW JERSEY.

CARPENTER'S TOOL.

1,134,806.

Specification of Letters Patent.

Patented Apr. 6, 1915.

Application filed May 21, 1914. Serial No. 839,991.

To all whom it may concern:

Be it known that we, WILLIAM H. BARRON, Jr., a citizen of the United States, and resident of Atlantic City, in the county of 5 Atlantic and State of New Jersey, and CARL LESEMAN, a citizen of the United States, and resident of Egg Harbor City, in the county of Atlantic and State of New Jersey, have invented certain new and useful 10 improvements in Carpenters' Tools, of which the following is a specification.

Our invention relates to tools for the use of carpenters, stair builders, cabinet makers, and others, and the main object is to provide 15 a tool which is adapted for a wide range of use as a marking gage, and also as a scribe, to mark work on regular or irregular lines.

A further object is to provide such a tool 20 which is adapted to accurately mark the skirting board of a stairway in one operation, with one marking.

A further object is to provide a tool of 25 this type which is adapted for use at either of its ends, and the marking elements at which ends are independently adjustable.

A further object is to so construct the 30 tool as to be capable of scribing circles, and also, in conjunction with a square, for scribing ellipses of any desired dimensions.

Our invention is fully described in the 35 following specification, of which the accompanying drawings form a part, in which the separate parts are designated by the same reference characters in each of the views, and in which:—

Figure 1 is a perspective view of the tool; Fig. 2 is a longitudinal section thereof; Fig. 3 is a view of the operation of marking the 40 positions of risers, in the skirting board of a stairway, with our tool; Fig. 4 is a similar view showing the operation of marking the positions of the treads therein; Fig. 5 is a view of the skirting board in place and 45 showing its connection with the base-board; Fig. 6 is a view of the method for using our tool as a scribe for circles; and Fig. 7 is a similar view for use in scribing ellipses.

Our invention consists of a straight rod a , 50 having a wheel or roller a^2 at one end thereof, and on said rod we mount an adjustable marking-wheel b , an adjustable needle-point c , and two adjustable guide-pins d and d^2 , carried in suitable blocks b^2 , c^2 , d^3 and d^4 ,

respectively, each of which has a set-screw 55 therein.

In Fig. 3 is shown the position of a skirting-board, with respect to a stairway, for marking the positions of risers, the said board being shown at f , the risers at f^2 and 60 the treads at f^3 , the gage being set at the required point, whereby the marking-wheel b , is at a distance from the wheel a^2 equal to the distance between the vertical planes 65 of the risers and, the riser lines may then be cut or scratched with the needle-point c which has been adjusted with reference to the wheel a^2 , this being repeated for all the 70 risers, as indicated in Fig. 3, and it will be noted that the lower end of the skirting-board f , when resting on the nosing of the treads for the marking just described, has been cut away on a horizontal line to allow 75 enough length of board for the baseboard joint, as shown in Fig. 5. After the risers have been so marked, or rather the intended 80 positions therefor, the gage is again set so that the marking-wheel b is at a distance from the wheel a^2 equal to the distance between the horizontal tread planes, the skirting-board having been slid upwardly on the 85 nosings of the treads into the position shown in Fig. 4, after which the positions of the treads are marked, the wheel or roller a^2 moving over the floor or successive treads 90 and the gage being maintained in vertical position, whereas in the marking of the risers, the roller a^2 moved over the risers of the stairway and the gage was maintained in horizontal position. After the said positions have been so marked, the holes for 95 the tread nosing are bored, and the skirting-board grooved therefrom for the treads and then the risers, and said board is ready for assembling on the stairway.

For scribing circles, all that is necessary is to move the wheel b and needle-point c apart a distance equal to the radius of the circle, said needle-point serving as the pivot for the circular movement of the marking 100 wheel b , and irregular outlines may be scribed with the gage by the use of either the needle-point or the marking wheel, in conjunction with the roller a^2 which is guided over the irregular surface which it 105 is desired to mark on a board or the like.

As clearly shown in Fig. 7, the device may be used to mark ellipses of any dimen-

2
sions within the limits of the rod *a*, the method of so doing being to draw line *x*—*x*, intersect the same with perpendicular line *z*—*z*, set the pin *d* at a distance from the wheel *b* equal to one-half the shortest diameter, and the pin *d*² a distance from said wheel equal to one-half the longest diameter, after which a square is arranged along the lines *x*—*x* and *z*—*z*, as shown, and one quarter of the ellipse may be marked by maintaining the guides *d* and *d*² in constant contact with the square, and moving the wheel *b* from the line *z*—*z* to the line *x*—*x*, the position of the square being changed 15 for each of the three remaining quarters of the ellipse.

It will thus be seen that our device is capable of great latitude in use, is very simple in construction, well adapted to the 20 purposes for which it is designed, and comparatively inexpensive and, reserving the right to make all desired changes in the same, within the scope of the following claims,

25 What we claim as new, and desire to secure by Letters Patent, is:—
1. A tool of the class described, comprising

ing a rod one end of which is forked, a shaft in said fork arranged in an axial plane of said rod, a roller carried by said shaft and arranged in an axial plane of said rod perpendicular to said first named plane, a block adjustable on said rod and a wheel on said block arranged transversely to the axis of said rod.

2. A tool of the class described, comprising a rod, one end of which is forked, a shaft in said fork arranged in an axial plane of said rod, a roller on said shaft arranged in an axial plane of said rod at 40 right angles to said first named plane, a block adjustable on said rod, a wheel on said block and arranged transversely to the axis of said rod, and a gage-block adjustable on said rod, said gage-block being provided 45 with a needle-point thereon.

In testimony whereof we have signed our names to this specification in presence of the subscribing witnesses.

WILLIAM HENRY BARRON, JR.
CARL LESEMAN.
